UNITED STATES PATENT OFFICE.

PETER DUNCAN, OF MOUNT OLIVER BOROUGH, PENNSYLVANIA.

BOX.

1,176,279.

Specification of Letters Patent. Patented Mar. 21, 1916.

Application filed April 24, 1915. Serial No. 23,633.

To all whom it may concern:

Be it known that I, PETER DUNCAN, a citizen of the United States of America, residing at Mount Oliver Borough, in the county of Allegheny and State of Pennsylvania, have invented certain new and useful Improvements in Boxes, of which the following is a specification.

The invention relates to an improvement in boxes designed particularly for use as containers of various commodities which are to be dispensed from time to time from the box, the particular construction of the box providing for its being divided or broken away as the quantity of the commodity is reduced, in order to provide a box of gradually reduced size to avoid the necessity of full box storage space when the box is but partly filled.

In the use of boxes as containers for many articles, such as cigars, confectionery, or article goods of any type, the articles are generally sold from the box in small quantities or singly so that a box of usual construction requires the same storage space were it completely full or containing but one or two articles. The present invention is designed to obviate this difficulty and permit the seller to reduce the size of the box in accordance with the quantity of material contained, so that the box accommodates itself in size to the quantity of material, thereby requiring only sufficient storage space for the actual material on hand.

The improved box is designed particularly to be readily reduced in size, for which purpose it is formed with a series of breaking kerfs or grooves in the sides, top and bottom, permitting the length of the box to be readily reduced to a uniform length by breaking along any particular line, the sides and ends being further formed intermediate the breaking grooves with undercut channels to receive a sliding cover so that the latter is adapted to coöperate with the box without regard to the length of the latter and seal the contents against deterioration.

The invention in the preferred form of details, will be described in the following specification, reference being had particularly to the accompanying drawings, in which:

Figure 1 is a perspective view of the improved box. Fig. 2 is a longitudinal section through the box. Fig. 3 is a similar view taken at right angles to Fig. 2. Fig. 4 is a

perspective view of the top or bottom. Fig. 5 is a perspective view of one of the sides.

Referring particularly to the accompanying drawings it will be noted that the improved box comprises top and bottom walls 1 and 2, of identical construction, side walls 3 and 4 of slightly different construction, an end wall 5 of plain construction and herein-after referred to as the fixed end wall and 60 an end wall 6 designed particularly for sliding coöperation with the top, bottom and side walls and hereinafter referred to as the sliding cover.

The top and bottom of the box are of identical construction, the said box being treated in the following description as if the plain end wall 5 was the lower end wall of the box. Each top and bottom wall is formed transversely thereof and throughout 75 the full width with a series of breaking grooves 7 which are practically saw kerfs extending slightly more than half way through the particular wall so as to compel the breakage of said wall along the line of 80 cut thus formed under slight lateral bending movement of the wall. The side walls are similarly formed with breaking grooves 8, and when arranged in box forming relation, as shown in Fig. 1, the breaking grooves of 85 the top and bottom walls and of one of the side walls register or align transversely of the box so as to present a breaking line at regular intervals throughout the length of the box and throughout the full contour of 90 the box, except at one side. One of the side walls as 3 and the top and bottom walls 1 and 2 are formed in addition to the breaking grooves with undercut channels 9, the channels include a ledge at right angles to the 95 face of the wall and an inclined surface extending upwardly and inwardly from the ledge. The channels 9 are located just below each breaking groove except the lowermost groove, the relative positions of the 100 channels and grooves arranging these elements in pairs, that is, each pair includes a breaking groove and a channel. The remaining side wall 4 is free of the channels 9 and simply formed with breaking grooves, 105 these grooves being spaced apart a distance corresponding to the spacing of the breaking grooves on the remaining side and top and bottom, but so initially spaced from the lower end of the particular side wall 4 as to 110 offset the breaking grooves of such side wall with relation to the breaking groove of the

other walls. In other words the breaking grooves and channels 9 of the top, bottom and side wall 3 are in exact registry one with another, while the breaking grooves of 5 the side wall 4 register with the ledge of the channels 9 of the other walls. By this construction when the respective walls are broken on the breaking grooves, the side wall 4, each time slightly shorter than the 10 remaining walls so as to expose the undercut channels of said walls.

The walls are secured in box forming relation as illustrated, and within the marginal edges of the lower end of said walls 15 is secured the end wall 5, which is perfectly plain, and nailed or otherwise secured in place, as may be desired. The opposite end of the box presents on three walls a channel 9, the remaining wall terminating in line 20 with the bottom or ledge of said channel. The cover 6 is formed with beveled edges at the side and one end to cooperate with the channel 9 of the top, bottom and side wall 3, said cover 6 overlying and resting upon the 25 free edge of the remaining side wall 4.

In this arrangement the box is completely closed and is serviceable as a container for any desired type of articles. As the number or volume of articles within the box diminish, it is the intention to reduce the size of 30 the box accordingly, to which end the respective walls are broken along the line of the particular breaking groove, which after breaking leaves the intact portion of the box 35 exactly as originally except in length, the breaking along the breaking grooves presenting fresh channels 9 to receive the sliding cover so that the latter is capable of use at all times as a closure.

40 It is of course to be understood that the box while preferably constructed of wood, is designed to be constructed of any material which can be severed along predetermined lines, and while preferably of the rectangular form shown, is also contemplated as being made up in any desirable form and of 45 any and all sizes.

Copies of this patent may be obtained for five cents each, by addressing the "Commissioner of Patents, Washington, D. C."

What is claimed is:

1. A box having the walls thereof formed with breaking grooves and with channels 50 to receive a cover.

2. A box having the walls thereof formed with breaking grooves and with channels to receive a cover, one of the walls being free 55 of the channels.

3. A box having the walls thereof formed with breaking grooves and with channels to receive a cover, one of the walls being free of the channels, the breaking grooves of such 60 wall being offset from the breaking grooves of the other walls in the completed box.

4. A box having the walls thereof formed with breaking grooves and with channels to receive a cover, one of the walls being free 65 of the channels, the breaking groove of such wall being alined with the channels of the remaining walls.

5. A box including top, bottom and side walls, a fixed end wall and a sliding cover, the top, bottom and side walls being formed 70 with breaking grooves, the breaking grooves of three of such parts being in alinement.

6. A box including top, bottom and side walls, a fixed end wall and a sliding cover, the top, bottom and side walls being formed 75 with breaking grooves, the breaking grooves of three of such parts being in alinement and having channels to receive the sliding cover.

7. A box including top, bottom and side 80 walls, a fixed end wall and a sliding cover, the top, bottom and side walls being formed with breaking grooves, the breaking grooves of three of such parts being in alinement, and having channels to receive the sliding 85 cover, the breaking grooves of the remaining part alining with the channels of the other parts.

In testimony whereof I affix my signature in presence of two witnesses.

PETER DUNCAN.
